UNITED STATES PATENT OFFICE

158,806

STUFFED, WINGED DOLL

Lewis E. Schwarz, Jr., New Orleans, La., assignor to Maison Blanche Company, a corporation of Louisiana

Application November 10, 1949, Serial No. 5,978

Term of patent 14 years

(Cl. D34—4)

To all whom it may concern:

Be it known that I, Lewis E. Schwartz, Jr., a citizen of the United States, residing at New Orleans, in the Parish of Orleans, and State of Louisiana, have invented a new, original, and ornamental Design for a Stuffed, Winged Doll, of which the following is a specification, reference being had to the accompanying drawing forming part thereof.

In the drawings:

The essential features of my design reside in the portions shown in full lines.

I claim:

The ornamental design for a stuffed, winged doll, as shown and described.

LEWIS E. SCHWARZ, JR.
